UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

ELECTRIC SWITCH.

1,290,899.

Specification of Letters Patent.

Patented Jan. 14, 1919.

Application filed February 5, 1916. Serial No. 76,248.

To all whom it may concern:

Be it known that I, GEORGE A. BURNHAM, a citizen of the United States, residing at Saugus, in the county of Essex and State of 5 Massachusetts, have invented an Improvement in Electric Switches, of which the following is a specification.

This invention relates to electric switches or circuit-breakers, which are adapted to 10 be employed in manholes and other more or less accessible places.

In such places it is desirable that the handle or other operating member shall be detachable, so that the switch or circuit- 15 breaker cannot be operated.

This invention has for its object improvements in this type of switch or circuit-breaker.

In accordance with my invention, the mechanism which is employed for operating the switch-elements, with the exception of the handle, is confined within a tight inclosing-case, and said mechanism has a handle-receiving member, which is adapted to be 20 engaged by a detachable handle, which handle may be carried about by the operator. Said confined handle-receiving member is arranged to be exposed, upon the removal of a plug, or some equivalent element, from a 25 hole in the wall of the case, to admit of the handle being engaged therewith.

As an additional feature of my invention, said plug is adapted to be removed by means of the same handle which is subsequently inserted through the plug-hole to engage the handle-receiving element, to operate the 30 switch-mechanism.

Another feature of my invention is the construction of the inclosing-case, especially 35 adapting it for use in damp or wet places.

Another feature of my invention is in the provision of means for mounting the switch elements upon a separate plate, whereby said switch elements may be assembled as a unit 40 and inserted in the switch-inclosing case.

Many features disclosed but not claimed in this application are disclosed and claimed in application Serial No. 76,249 filed February 5, 1916.

Figure 1 is a front elevation and partial section of an electric switch or circuit-breaker embodying this invention.

Figs. 2 and 3 are sectional details of portions of the operating-mechanism.

Fig. 4 is a fragmentary detail illustrating

particularly the socketed plug which closes the opening in the wall of the case, through which access to the confined operating-mechanism is obtained.

10 represents the oil-can, or receptacle, which is of any suitable shape and dimensions. As here shown, it is made flaring at the top, so that its top-portion overhangs the can. 12 is a cover arranged to be fitted tightly on top of said can, and to be secured thereto by bolts or other means. A screw-eye 13 may be secured to the top of the cover. 15 and 16 represent two stationary switch-elements, arranged in insulated bushings 17 and 18, which latter are supported by a plate 19, arranged horizontally in the top part of the can, and resting upon ears 20, and secured thereto by screws or other means. Said supporting-plate is adapted to tightly close the oil-containing compartment of the receptacle, although ventilation may be provided, if desired. This method of securing the switch elements upon a supporting plate admits of the complete assembly of the switch elements independent of the receptacle, and their assembly therein or removal therefrom, as a complete unit. The upper ends of the switch-elements 15 and 16, have binding-means 21 and 22, by which the circuit-wires 23, 24, are connected therewith, and said wires extend outward through insulated bushings 25, fitted in holes in the bottom part of the overhanging top-portion of the case, which bushings are extended downwardly, so that moisture which collects in the case will flow down and will not have any tendency to enter the case.

30 represents the movable switch-element having a vertically movable rod 31, said element being movable into and out of engagement with the stationary switch-element. There may be any desired number of pairs of stationary switch-elements, and corresponding movable switch-elements.

A lever 35, is pivotally connected at one end, as at 36, to the movable switch-element, its other end being pivoted at 37 to an ear 38, rising from the supporting-plate 19. There is a toggle connected with said lever 35 near the pivot 37. One member 40 of the toggle, is loosely connected with the lever 35, intermediate its length, and the other member 43, has a hub 44, arranged in bearings in the ear 38, and extended through said ear and held against endwise movement. The hub 44 has

5 a center-hole 60, which is formed with a key-way adapted to receive a detachable handle, so that said hub serves as the handle-receiving element of the operating-mechanism. In 10 lieu of this form of operating-mechanism for the switch-elements, any other form may be employed, so far as my present invention is concerned.

10 The handle-receiving element of the operating-mechanism is arranged opposite a hole through the wall of the receptacle 10, so that a handle 65, having an end-portion 66 of a shape and size in cross-section corresponding to the shape and size of the hole in 15 the hub, may be projected through said hole in the wall and into said hub thereby to connect the handle with the hub for the purpose of turning said hub to operate the toggle and move the lever 35, and switch- 20 element connected therewith.

In Fig. 2, the handle is represented as connected with the hub, and in Fig. 4, an end view of the hub with its annular ring, is shown.

25 Excepting when it is desired to operate the switch, the handle is removed or disengaged from the hub, and the hole in the wall of the case is tightly closed by a screw-plug 70, or equivalent closure, see Fig. 2. Said plug, 30 as here shown, has an external socket with a keyway of a shape and size corresponding to the end-portion of the handle, so that said end-portion may be projected into said socket and the handle thus used to turn the 35 plug; or other handle-engaging means may be provided on the plug.

It will be observed that when the handle is disengaged and the hole in the wall of the inclosing-case closed by the plug, the 40 operating-mechanism for the switch elements, and the switch elements are confined within a tight inclosing case.

I claim:

1. In an electric switch, an inclosing casing, comprising an oil receptacle and a cover 45 ing, comprising an oil receptacle and a cover therefor, said oil receptacle having bushings extended through the top part of the walls thereof for the passage of switch leads into the casing, a plate disposed in said oil receptacle below said switch lead bushings and detachably secured to said casing, a switch unit supported by said plate and adapted to be entirely inclosed by said casing comprising stationary switch contacts depending 50 from said plate having extensions extended above said plate for connection with switch leads, movable switch members, and operating mechanism for said movable members, a component part of said operating mechanism extending into proximity with a wall 55 60

of said oil receptacle and having a handle engageable portion for connection with a detachable handle by which the switch may be operated, an opening through the wall of said oil receptacle in alignment with the handle engageable portion for the insertion of the detachable switch handle and a plug normally sealing said opening against entrance of water, said plate and said switch unit, comprising said stationary contact 70 members, movable switch members and operating mechanism, being removable from said oil receptacle, and said casing, when said cover is thereafter secured to said oil receptacle, being sealed against entrance of 75 moisture.

2. In an electric switch, an inclosing casing, comprising an oil receptacle and a cover therefor, said oil receptacle having insulating bushings extended through the top part 80 of the walls thereof for the passage of switch leads into the casing, a plate disposed in said oil receptacle below said switch lead bushings and detachably secured to said casing, a switch unit supported by said plate comprising stationary switch contacts depending from said plate and having extensions extended above said plate for connection with the switch-leads, movable switch members, and operating mechanism for said 85 movable members, all of said operating mechanism and switch members adapted to be entirely inclosed within said casing, a component part of said operating mechanism being arranged in proximity with a 90 wall of said receptacle and having a handle engageable portion adapted to be engaged by a detachable switch operating handle inserted through an opening in the wall of 95 said receptacle, said oil receptacle having an 100 opening in a wall thereof in alignment with the handle engageable portion of said component part of the said operating mechanism, a plug in said opening normally sealing 105 said opening against entrance of moisture and removable therefrom to permit the insertion of a switch operating handle, said plate with said switch members being removable from said casing and said cover being thereafter replaceable and said casing 110 is thereby sealed against entrance of moisture.

In testimony whereof I have signed my name to this specification in the presence of two subscribing witnesses.

GEORGE A. BURNHAM.
